UNITED STATES PATENT OFFICE

141,577

DESIGN FOR AN ELECTRICAL POLISHING DEVICE

Samuel Resnick, Oak Park, Ill.

Application March 13, 1945, Serial No. 118,459

Term of patent 7 years

(Cl. D9—2)

To all whom it may concern:

Be it known that I, Samuel Resnick, a citizen of the United States, residing at 28 West Washington Blvd., Oak Park, in the county of Cook and State of Illinois, have invented a new, original, and ornamental Design for an Electrical Polishing Device, of which the following is a specification, reference being had to the accompany drawing forming part thereof.

Fig. 1 is a side elevation of an electrical polishing device embodying my design;

Fig. 2 is a plan view of same; and

Fig. 3 is an end view of same.

I claim:

The ornamental design for an electrical polishing device, as shown.

SAMUEL RESNICK.
